RADIATOR COMPOSED OF REMOVABLE ELEMENTS

Camille Mical, Asnieres, France

Application January 9, 1936, Serial No. 58,394
In France January 26, 1935

2 Claims. (Cl. 257—125)

This invention relates to a radiator composed of removable elements in which the upper and lower water tanks receive, in the known manner, the headers of the various bundles of heat exchanging tubes, arranged parallel to each other.

The radiator of this invention is made up of separate elements arranged for assemblage into radiator form or disassemblage at will to provide for removal of and permit accessibility to the 10 radiator tubes; the construction including valves for establishing water communication between the tubes and fixed tanks of the radiator, with the means for connecting or disconnecting the radiator parts providing for simultaneous control of the valves during disconnection. For that purpose, the water tanks carry hollow cross members forming channels and projecting forwardly for allowing to fit therein the corresponding headers of the bundles of heat exchanging tubes. 15 Each cross member encloses any valve the rod of which extends outwardly and is terminally formed to provide a terminal corresponding to a screwdriver end. The rod is screw-threaded, so that it can be screwed in the cross member when 20 a blind nut drives it, by means of the screwdriver, by itself screwing on the screw-thread of the front end of said cross member. By means of these arrangements, any angular displacement 25 of the blind nut, in one direction or the other, simultaneously produces translations, in the same 30 directions, of the valve.

This device is of particular advantage when the heat exchanging surface of the radiator is relatively large, as, for instance, for motor lorries.

In the accompanying drawing:

Fig. 1 is a front view of a radiator constructed according to the invention.

Fig. 2 is a vertical section of the radiator.

Fig. 3 is a vertical longitudinal section of an 40 element connecting the bundle of tubes to the water tanks.

Fig. 4 is a section made according to line 4—4 of Fig. 3.

Fig. 5 shows a modification in the mode of 45 securing the bundle of tubes in position.

The upper and lower water tanks 1 and 2 are formed in their rear portions with offsets 3 which extend the full length of the tanks and are in open communication therewith. The offsets on 50 the respective tanks extend toward the opposite tank and each tank in advance of its offset extends forwardly for the remaining dimension of the tank in the form of narrow hollow sections in full communication with the tank and defining 55 between them spaced channels, the upper por-

tions of which are preferably rounded, as clearly shown in Figure 1. In each channel is arranged a hollow sleeve-like cross member 4, the rear end of which is removably secured in a non-leaking manner in the vertical wall of the particular offset 3. These cross members 4 thus form upper and lower rows and serve for the assemblage of the heat exchanging tubes 5. For that purpose, the elements of each bundle are inserted, at their upper and lower ends, in plates 6 constituting 10 the wall of common headers 6a. Each header 6a fits slidably over the cross member 4. The member 4 is screwed in the reinforced wall of the tank and secured by a nut 7, then the header 6a formed with suitable holes 6b is slipped over 15 the fixed member and retained thereon by a nut 7. Washers 8 are provided to prevent leakage.

The front end of the cross members 4 is internally screw-threaded for allowing the corresponding portion of the rod 9 of a valve 10 to be 20 screwed therein. The front end of the rod 9 has an extension 15 forming a screwdriver. Its inner end is provided with a cylindrical bearing portion 11 terminating in the conical valve 10.

On the screw-threaded portion 12 of the front 25 end of the cross member 4 is screwed a cap 13, in the bottom of which is provided a recess 14 for the screwdriver form terminal 15. In these conditions, when the cap 13 is screwed on the cross member 4, the rod 9 of the valve is simultaneously screwed, by means of the screwdriver 15, in the internally screw-threaded portion of 30 said cross member 4. The valve 10 thus receives a helical displacement which moves it away from its seat 16. The water tank is thereby put in 35 communication with the corresponding header of the bundle of heat exchanging elements.

Reversely, the unscrewing of the cap 13 causes 40 the valve 10 to be moved in the reverse direction. The externally and internally screw-threaded portions are such that the cap 13 cannot be separated from the cross member before the valve is completely closed. As a result of this construction, any group of heat exchanging elements can be removed at will for repair or replacement.

The arrangement described can moreover be so 45 devised as to allow the degree of opening of the valves 10 to be adjusted, and this for the purpose of controlling the capacity of heat dispersion of the apparatus. Consequently, it will be understood that it suffices to control the number of revolutions imparted to the screw-threaded rod 9 of valve 10 in the internally screw-threaded 50 portion of the fixed cross member 4.

A simple means, allowing an easy control, con- 55

sists in covering the operating cap 13 with another cap 17 constituting an abutment for the cross member 4; the relative longitudinal positions of the operating cap 13 and of the abutment-cap 17 being determined by interposition between said caps of intermediate washers 18. For that purpose, the operating cap 13 is provided with an extension constituted by an end piece 19 having flat side portions and terminating in a screw-threaded member 20. This end piece 19 passes through an opening, of the same shape as its cross section, formed in the bottom of the abutment-cap and it externally receives, on its screw-threaded portion, a nut 21. The washers 18 are provided with an opening the shape of which allows them to be fitted over the end piece 19 and the outer diameter of which is such that they can be inserted within the abutment-cap. In this way, the washers 18 can be either all external, or all internal, or some external and the others internal.

The longitudinal relation of the operating cap 13 relative to the bearing face of the abutment-cap 17 may thus be varied. As the longitudinal relation of the cap 17 to the operating cap 13 will control the extent to which the cap 13 may be screwed in place before the cap 17 reaches its limit of movement, it is apparent that this variation of longitudinal position between the caps 17 and 13 will determine the opening extent of the valve 10. Thus, the movement of any one of the valves 10 and consequently fluid communication between the water tank and header controlled by such valve may be readily varied at will.

It is intended that the washers 18 be fixed in number in any installation and that where the fixed number of washers 18 are arranged within the cap 17 and between it and the cap 13 in order to permit maximum screwing movement of the cap 13, the knowledge that all of the washers are between the caps will indicate that the particular valve 10 has been opened to its maximum. Where adjustment of this opening is desired, one or more of the washers 18 will be removed from a position between the caps and placed exteriorly of the cap 17 between it and the

nut 21. The externally placed washers being visible will indicate a corresponding absence of such washers between the caps 13 and 17 and also indicate a correspondingly limited movement of the cap 13 before the abutment cap 17 reaches its limit. This limited movement of the cap 13 will, of course, compel a correspondingly limited opening movement of the valve 10, and thus the user, by noting the number of washers between the cap 17 and the nut 21 or the absence of such washers in such position, will at once be advised as to the extent to which the particular valve 10 has been opened.

The possibility of putting selected bundles of heat exchanging elements out of service or of varying the positions of the valves permits the cooling capacity of the radiator to be adapted to the thermo development of the engine.

Constructional modifications can be made in the arrangements described and illustrated without departing thereby from the scope of the invention.

I claim:

1. A radiator comprising upper and lower water tanks, removable radiator elements having upper and lower headers, tubular members fixed on and communicating with said water tanks, said headers having holes adapted to be passed over said tubular members and said tubular members having lateral openings adapted to communicate with said headers, a valve associated with each tubular member, having a rod screwed in said tubular member and operable by rotation to open and close the communication from said water tank to said header, nuts screwed on said tubular member for fixing said header to said tank, a closure cap screwed on the end of said tubular member and interengaging parts formed on said valve rod and closure cap, so that unscrewing of said closure cap will cause rotation of the valve rod so as to close the valve.

2. A radiator as claimed in claim 1, including an abutment cap fitted over said closure cap and a variable number of spacing washers placed between said caps.

CAMILLE MICAL.
